UNITED STATES PATENT OFFICE.

ALBERT J. OTT AND CONRAD L. OTT, OF DETROIT, MICHIGAN, ASSIGNEES TO AMERICAN GRINDER CO., OF DETROIT, MICHIGAN, A CORPORATION OF MICHIGAN.

GEAR-GRINDING MACHINE.

Application filed January 29, 1923. Serial No. 615,583.

The invention relates to machines for grinding gears and particularly to a type of machine in which the tooth contour is developed by means of a generating movement.

The object of the invention is the provision of a compact machine for the rapid production of accurately ground gears, that is, gears having teeth of proper contour and accurate spacing, both of which conditions are necessary for the quiet running of intermeshing gears.

This is accomplished as follows: first, by quick loading of the gear to be ground properly aligned with the grinding mechanism; second, by a work driving mechanism which positively reciprocates the slide carrying the work and is provided with a quick return, thereby reducing the time for each cycle of operation to a minimum consistent with grinding practice; third, by automatically stopping the work for detaching the ground gear; fourth, by placing all control levers within easy reach of the operator, and; fifth, by the arrangement of the component parts of the machine to provide accessibility in order that adjustments may be easily made for grinding gears of different sizes and forms.

In general construction the machine consists of a base A, to which is secured a rotatable grinding wheel B having a plane surface arranged at an angle with the work corresponding to the pressure angle of the gear tooth to be ground. The base is provided with guide ways D for carrying a slide E on which is journaled a work holding arbor F. The slide is reciprocated by means of a cam drum G having a suitable cam slot therein cooperating with a roller secured to said slide to impart the desired reciprocatory motion. In order to produce a generating movement for grinding the gear teeth, the work arbor F is rotated corresponding to its reciprocation thereby causing a relative rolling movement of the work and the grinding wheel corresponding to the intermeshing of the gear with a rack tooth. For this purpose a cylinder H of a diameter equal to the pitch circle of the gear is journaled in alignment with the arbor F and flexible tapes I are wound therearound and extended in opposite direc-

tions in a plane tangential to the cylinder where they are secured to a table on the base of the machine. The cylinder H is connected to the arbor F through an indexing mechanism J which normally transmits the rotation of the cylinder to the work arbor. Thus by reciprocating the slide E a rolling movement is imparted to the gear C which generates the contour of the gear tooth.

In the rearward stroke of the reciprocation of the slide E the gear C is carried out of engagement with the grinder wheel B and in order to provide for the indexing after the gear has entirely cleared the grinder wheel, the slide is still continued backward an amount corresponding to the rotation of one gear tooth. On the forward stroke of the slide the indexing mechanism uncouples the cylinder H from the arbor F and during the first portion of the forward stroke the arbor is moved without rotation an amount corresponding to the rotation of one gear tooth whereupon the cylinder is again coupled with the arbor and the rolling motion again imparted to the gear blank to bring the next successive tooth in contact with the grinder wheel. In this manner each reciprocation of the slide causes a successive tooth to be ground until each of the teeth have been finished, when an automatic stop mechanism K operates a clutch L for disconnecting the driving means and stopping slide E.

One of the features of the construction is the arrangement of the arbor F and the tapes I and it will be noted that the work is located at one end of the arbor while the cylinder H and the tapes I are at the opposite end and the guideways D are located centrally of the arbor. With this construction the tapes are readily accessible and may be easily adjusted and cylinder H may be very small in diameter making it possible to grind small gears.

Another feature is the arrangement of the driving mechanism for by positively actuating the slide by means of a drum cam the rearward reciprocation of the slide is made quicker than the forward stroke, thereby increasing the production speed. Also in this construction the tapes are used only for rotating the work holding arbor and are,

therefore, not subjected to excessive loads and the shocks due to the inertia of the moving carriage.

In the drawings:—

5 Figure 1 is a front sectional elevation of the machine taken on the line 1—1 of Figure 2;

10 Figure 2 is a transverse section on the line 2—2 of Figure 1 looking from the left side of the machine;

15 Figure 3 is a section on the line 3—3 of Figure 1 looking from the right side of the machine with the grinder wheel mechanism removed;

20 Figure 4 is a longitudinal section on the line 4—4 of Figure 3 looking from the rear of the machine;

25 Figure 5 is a rear view showing the indexing mechanism and the tapes for actuating the work spindle;

30 Figure 6 is a plan view of the indexing mechanism shown in Figure 5;

35 Figure 7 is a similar view to Figure 5 showing the operation of the indexing mechanism;

40 Figure 8 is an enlarged longitudinal section of the automatic stop mechanism on the line 8—8 of Figure 3;

45 Figure 9 is a similar view to Figure 8 with the parts shown in elevation;

50 Figure 10 is a side elevation of the entire machine;

55 Figures 11 and 12 show two positions of the gear in rolling engagement into the grinder wheel;

60 Figure 13 illustrates the position of the gear during the indexing movement;

65 Figure 14 shows the development of the cam drum G;

70 Figure 15 is a plan view of the mechanism shown in Figure 1 for locating the gear with respect to the grinding wheel.

75 The grinder wheel B is rotatably mounted on a vertically adjustable carriage 1 which slides upon the vertical ways 2 on the base A. Preferably, the wheel is of relatively large diameter in order that the root of the tooth may be ground without providing a

80 relative movement of the grinder wheel longitudinally of the gear teeth. The plane of the grinder wheel B is disposed at an angle to the plane of the work slide E, this angle being equal to the pressure angle of the gear tooth to be ground thereby forming in effect

85 a rack tooth with which the gear C intermeshes. The grinding surface of the wheel B is shown at 3 while the opposite surface 4 is tapered to provide clearance between the back edge of the wheel and the tooth adjacent to the one being ground. The grinder wheel B is suitably secured upon a hub 5 by means of an annular ring 6 and the screws 7

90 threadedly engage a flange 8 thereby clamping the grinder wheel to the hub. 9 is an arbor which is journaled in tapered bearings

95 in a housing 10 adjustably arranged at an angle to the carriage 1 corresponding to the pressure angle of the gear tooth. The housing is pivoted to the carriage on a stud 11 and secured at the desired angle by the bolts 11^a which are inserted through arcuate slots 11^b in the housing and threadedly engage the carriage. A suitable scale 12 is provided for indicating the angle at which the housing is set. The lower end of the shaft is tapered 100 at 13 for receiving the hub 5 which is keyed thereto and held into engagement by the threaded cap 14. To prevent longitudinal movement of the shaft 9 there is provided a thrust bearing 15 which is housed in a cylindrical member 16 threadedly engaging the hand wheel 17. The latter is rotatably mounted upon the housing 10 and provided with a graduated scale 18 so that longitudinal adjustment of the shaft 9 may be effected by rotation of the hand wheel. Keyed upon the shaft 9 is the pulley 19 which is connected with suitable driving means, not shown, for rotating the grinder wheel. A grinder wheel housing 20 is secured to the shaft housing 10 by the bolts 21 and incloses the entire wheel with the exception of the top portion for engaging the gear wheel C.

105 In order to generate the surface of the gear tooth the work arbor must be given both a rotary and a reciprocatory motion and the frame is, therefore, provided with the horizontal guide-ways D on which is mounted the slide E. For reciprocating this carriage there is a depending pin 22 on which is journaled a roller 23 engaging in the cam slot 24 of the cam drum G. This cam slot is arranged to give the desired reciprocatory motion for one revolution of the cam drum and it is preferably so shaped that on the forward stroke of the carriage the latter is given a substantially uniform motion while the grinder wheel is in engagement with a gear tooth, but on the rearward stroke the speed is increased, thereby completing the 110 cycle in a shorter period of time than with the usual forms of driving mechanism.

115 The cam drum is mounted upon a shaft 25 journaled at 26 in the frame A and receives its power from a shaft 27 also journaled in the frame A by means of a suitable train of gears 28, 29, 30, and 31. 32 is a driving pulley journaled in alignment with the shaft 27 and connected thereto by a clutch 33 provided with teeth 34 for engaging corresponding teeth 35 of the pulley 32. The pulley 32 receives its power from a driving motor or other suitable means.

120 Journalized in the slide E transversely to the ways D is the arbor F which carries at 125 its outer end a spindle 36 upon which the gear to be ground is mounted and clamped against the shoulders 36^a by a nut 36^b threadedly engaging the spindle. Mounted in alignment with this arbor is the cylinder H 130

which extends outward to the rear of the machine and is provided with the flexible tapes I wound therearound in alternate directions and extended out in a plane tangential to the cylinder and parallel to the guideways D. The tapes are secured to the cylinder by the clamps 37 and the bolts 38 while the outer ends are clamped to a horizontal carriage 39 mounted in guideways 40 on a vertically adjustable carriage 41 upon the base A. The cylinder is connected to a flange 42 which is secured to a second flange 43 journaled in a bearing 44 in the slide E. Within these flanges 42 and 43 is an indexing wheel 45 which is secured to the work arbor F and is normally locked in engagement with the flanges thereby coupling the cylinder H and the arbor F. Thus when the slide E is reciprocated, the arbor F is given a rolling motion with respect to the grinding wheel B.

In order to index the machine whereby each reciprocation will grind a successive gear tooth, the index wheel 45 has arranged around the periphery thereof slots 46 corresponding to the number of teeth to be ground. The flange 43 is provided with a radial guideway 47 in which an index plunger slide 48 is inserted. The slide has secured thereto a laterally extending plunger 48^a adapted to engage with the slots 46 and normally held in engagement by a spring 49 disposed between a lateral flange 50 of the slide and a seat 51 upon the flange 43. The slide is formed with a tail portion 52, the outer surface of which forms a circumference of a circle concentric with the index wheel and a roller 53 is journaled on the under side of the slide. During the oscillation of the cylinder H the slide 48 is rotated with the flange 43 and normally carries the index wheel 45 therewith. In order to disengage the plunger 48^a during the forward portion of the oscillation a member 54 is pivoted upon the carriage of the machine in the path of the roller 53 and is provided with a cam surface 55 normally held in the path of the roller 53 by a spring 56. The arrangement is such that the roller trips the member 54 at the completion of its rearward oscillation and on the forward stroke the roller rides upon the cam surface 55 thereby moving the index plunger slide 48 radially outward and disengaging the plunger 48^a from the slot 46 in the index wheel.

56' is a stop plunger arranged in alignment with the slot 46 from which the plunger 48^a is withdrawn by the cam surface 55. The plunger is normally held out of engagement by means of a spring 57. 58 is a rocker arm pivoted upon the carriage of the machine and having the arms 59 and 60, the former extending adjacent to the plunger 56 and the latter provided with a roller 61 arranged in the path of the tail 52 of the

index plunger slide 48. As shown in Figure 7 during the forward movement of the carriage the slide 48 is moved radially outward by the cam surface 55 thereby engaging the roller 61 with the tail portion of the slide 48. This rocks the arm 58 and inserts the stop plunger 56' in the slot 46 of the index wheel from which the plunger 48^a has been removed. In continuing the forward movement the slide 48 is rotated but the index wheel is held stationary by the stop plunger 56'. However, as soon as the plunger 48^a has been moved into alignment with the next slot 46 it is forced therein by the spring 49 and as the roller 61 is now free from the tail 52 the plunger 56' is withdrawn by the spring 57. During the remainder of the forward stroke the index wheel is again coupled to the flanges 42 and 43 and the work is given a rolling motion with respect to the grinder wheel.

With the machine as thus far described it will be seen that during each cycle the gear is rolled into and out of engagement with the grinder wheel to generate the contour of one gear tooth and at the end of each reciprocation the gear is indexed to bring an adjacent tooth into engagement with the grinder wheel. This cycle is continued until all the teeth have been ground and in order to stop the operation of the machine at this point there is provided a mechanism for releasing the clutch 33 from the driving pulley 32.

A sleeve 58' surrounds the shaft 27 and is mounted upon the base of the machine by means of a bracket 59'. 60' is a spring attached at one end to an arm 61' upon the sleeve 58' and at the other end to a clutch lever 62 engaging in an annular slot 63 in the clutch 33. The shifting lever is supported upon an arm 64 of a rocker lever 65 pivotally attached to the bracket 58' by a pin 66 and provided at its other end with an arm 67 extending at right angles to the arm 64. For actuating the rocker lever there is a handle 67' upon one end of a lever 68 pivotally supported at 69 and connected to the arm 67 by a cross link 70. Normally the clutch 33 is held out of engagement by the spring 60' but by operating the handle 67' it is moved into engagement with the teeth 35 of the pulley 32 thereby starting the slide E in operation.

A spring pressed lever 71 pivoted at 72 engages with a lug 73 upon the handle 67' and locks the same to hold the clutch in engagement. For disengaging the clutch it is necessary to actuate the lever 71 against the tension of the spring 74 and for this purpose a ratchet mechanism is employed actuated by the reciprocation of the carriage after a predetermined number of cycles. In detail this mechanism comprises a ratchet wheel 75 which is journaled upon a pin 76

supported by the upwardly extending portion 77 of the frame A. 78 is a dial also journaled upon the pin 76 and provided with a boss 79 at the periphery thereof in which is inserted a longitudinally slideable pin 80 having at the lower end thereof a ratchet tooth 81 engaging with the ratchet wheel 75. A spring 82 normally holds the tooth 81 in engagement with the ratchet wheel while a knob 83 is used for withdrawing the same. 84 is a stop lever mounted upon the pin 76 and adjustably clamped against the shoulders 76^b in order that it may be set in any predetermined position corresponding with the numbers upon the dial 78. For operating the ratchet wheel there is a spring pressed pawl 85 pivoted upon an arm 86 journaled upon the pin 76. A cam surface 87 upon the arm 86 is arranged in the path of a dog 88 carried by a member 89 actuated by the slide E. The arrangement is such that upon each reciprocation of the slide the dog 88 rides upon the cam surface 87, thereby advancing the ratchet wheel 75 one tooth. 85' is a stop pawl engaging the ratchet wheel 75, allowing it to move in only one direction. The ratchet wheel carries with it the dial 78 and the tooth 81 and after a predetermined number of reciprocations the tooth is brought into registration with a cam surface 90 upon an arm 91 of the lever 71 and the cam surface 92 upon the tooth cooperates with the cam surface 90 to trip the lever 91, thereby withdrawing the lever arm 71 from the dog 73 upon the handle 67'. The clutch is then automatically thrown out by the operating spring 60'.

The stop arm 84 may be set to correspond with the number of teeth upon the gear to be ground and when it is desired to start the machine in operation the tooth 81 is withdrawn from engagement with the ratchet wheel 75 by means of the handle 83 and the latter is then rotated until it strikes the stop 84. Upon the movement of the handle 67 to operate the clutch, the lever 71 springs into position and prevents the handle from returning thereby holding the clutch in engagement until the tooth 81 is again rotated by the ratchet mechanism into engagement with the cam surface 90.

If it is desired to stop the machine before the completion of the gear the lever 71 may be manually tripped by operating the handle 93 which is mounted on the lever arm 91.

As previously mentioned the gear C is clamped against the shoulders 36^a of the arbor F by means of a nut 36^b and in replacing a finished gear with a new blank it is necessary to accurately position the same on the arbor in order to insure the proper engagement with the grinder wheel. For this purpose a shaft 94 is mounted in the slide E parallel to the arbor F and is provided at

its outer end with a slotted member 95 clamped upon the shaft and provided with ears 96 for mounting a lever 97 extending transversely to the axis of the shaft 94 and pivotally secured to the ears by the bolt 98. Secured to one end of the lever 97 is a finger 99 having at its outer end a tooth 100, one surface of which is adapted to engage with the teeth of the gear C. This surface 101 is arranged at an angle with the center line 75 between the shaft 94 and the arbor F corresponding to the pressure angle of a gear tooth to be ground. The member 95 is provided with a spring pressed plunger 102 engaging the lever 97 at the opposite side of 80 the pivot 98 from the finger 99. By means of this spring pressed plunger the finger 99 is normally held out of engagement with the gear wheel C but by manually pressing upon the arm 103 of the lever 97 the finger 99 may be brought into engagement with the gear C as shown in the dotted lines in Figure 15.

Since the gear blank C is rotating with respect to the finger 99 during the reciprocation of the slide E it is necessary to stop 90 the slide E in a predetermined position when it is desired to use the finger 99 for aligning the gear C with the grinding mechanism.

This is accomplished by the automatic stop mechanism previously described, which is so arranged that the slide is stopped at one extreme position of its reciprocation. The dwell 24^a in the cam slot of the cam drum is of sufficient length to allow the slide to be completely stopped while the roller 23

engages therein and in this manner the slide is always stopped in a predetermined position of its cycle. By properly positioning the tooth 100 upon the finger 99 it may be used to position the gear C upon the arbor 100 F so that it will properly mesh with the grinder wheel during the subsequent operation.

In replacing a new gear blank upon the arbor F it is placed upon the spindle 36 and the finger 99 is brought into engagement 105 with a tooth by manually pressing the lever 97 against the action of the spring pressed plunger 102. The gear may then be rotated upon the spindle until the gear tooth engages with the tooth 100 of the finger 99

whereupon it may be secured to the arbor by means of the nut 36^b. As soon as pressure is released from the lever 97 it will automatically return to inoperative position. 115

In Figures 11, 12, and 13, the method of rolling the gear blank C upon the grinder wheel B is illustrated. The gear C is shown

rotating clockwise about the center 104 and having a motion of translation to the right in the direction of the arrow which corresponds to the rearward reciprocation of the slide E. The tooth 105 meshing with the grinder wheel B in Figure 11 is shown in Figure 12 in a position about to leave the grinder and the rearward motion continues 125 130

until, as shown in Figure 13, the gear is entirely clear of the grinder. Upon the forward motion of the slide E the gear is moved to the left without rotation a distance corresponding to the rotation of one gear tooth when the rolling motion is again imparted thereto and it will be noted that the tooth 105 will clear the periphery of the grinder wheel while the tooth 106 will engage the same and as the forward motion continues will roll upon the grinder wheel in the same manner as represented in Figures 12 and 11.

In Figure 10, the side elevation of the entire machine is shown illustrating a motor 107 mounted upon the base A and driving a counter-shaft 108 which is controlled by a clutch 109 operated by the lever 110 extending within easy reach of the operator. While the machine is shown as being motor driven it is obvious that any other suitable source of power might be connected to the shaft 108. A pump 111 mounted upon the base of the machine is driven from the shaft 108 and may be used for supplying a cooling fluid to the grinder wheel.

For truing the grinding surface 3 there is provided a trimming mechanism 112 consisting of a lever 113 pivotally supported upon a bracket 114 mounted upon the housing 10 in such a manner that the plane of rotation of the lever is parallel to the plane of the grinding surface 3. A lateral extending arm 115 mounted upon the lever 112 contains a trimmer 116 adjustable by means of the knob 117.

What we claim as our invention is:—

1. A gear grinding machine comprising a frame, a grinder wheel having a working surface lying in a plane inclined at an angle to the horizontal axis of the work, said grinder wheel being of relatively large diameter whereby it is adapted to simultaneously operate over the entire width of a gear tooth, an arbor adapted to receive the gear to be ground, said arbor being arranged above said grinder wheel, and means for simultaneously imparting horizontal reciprocatory movement and oscillatory movement to said arbor whereby the gear is given a rolling generating movement with respect to said working surface.

2. In a gear grinding machine, the combination of a frame having guideways thereon, a carriage reciprocable on said guideways, a work holding arbor journaled on said carriage, a rotatable grinder wheel in operative relation with the work on said arbor, a cam follower secured to said carriage, a rotatable drum having a cam groove on the periphery thereof adapted to cooperate with said cam follower to reciprocate said carriage, said cam groove being so formed as to impart a faster movement to said carriage during a portion of the cycle while the grinder wheel is not in grinding engagement with the work,

means for rotating said drum, a rotatable member normally connected to said arbor and flexible tapes wound upon said rotatable member and secured to said frame to impart a rolling motion to the work with respect to said grinder wheel.

3. In a gear grinding machine, the combination of a frame having guideways thereon, a carriage reciprocable on said guideways, a work holding arbor journaled on said carriage, a rotatable grinder wheel in operative relation to the work on said arbor, a cam follower upon said carriage, a rotatable drum having a cam groove on the periphery thereof adapted to cooperate with said cam follower to reciprocate said carriage, said cam groove being so formed as to impart a relatively slow feeding movement and a relatively faster return movement to said carriage, means for rotating said drum, a rotatable member upon said carriage normally coupled to said arbor, and flexible tapes wound upon said rotatable member and secured to said frame to impart a rolling motion to the work with respect to said grinder wheel.

4. In a gear grinding machine, the combination with a rotatable grinder wheel, of a work holding arbor, means for simultaneously reciprocating and rotating said arbor relative to said grinder wheel to generate a gear tooth on the work, means for automatically indexing said arbor after each reciprocation to present a successive tooth to said grinder wheel, and means for automatically stopping the reciprocation of said arbor after a predetermined number of the teeth have been ground.

5. In a gear grinding machine, the combination of a frame having guideways thereon, a carriage reciprocable on said guideways, a work holding arbor journaled on said carriage, a rotatable grinder wheel in operative relation with the work, a cam for reciprocating said carriage, means for rotating said arbor corresponding to the reciprocations thereof to impart a rolling motion to the work, means for driving said cam, a clutch between the driving means and said cam, a spring for yieldingly holding said clutch out of engagement, a lever for throwing said clutch into engagement against the action of said spring, a spring catch engageable with said lever to hold said clutch in engagement, a ratchet wheel operable by the reciprocation of said carriage, and a trip carried by said ratchet wheel for releasing said spring catch after a predetermined number of reciprocations.

6. In a gear grinding machine, the combination with a rotatable grinder wheel, of a work holding arbor, means for simultaneously reciprocating and rotating said arbor relative to said grinder wheel to generate a gear tooth on the work, means for stop-

ping the movement of said arbor in a pre-determined position of its cycle, and means engageable with the work when in said pre-determined position for angularly locating the same upon the arbor, whereby a tooth of the work will mesh with said grinder wheel during the subsequent movement of said arbor.

7. In a gear grinding machine, the combination with a rotatable grinder wheel, of a work holding arbor, means for securing a gear upon said arbor, a cam for reciprocating said arbor relative to said grinder wheel, said cam being provided with a dwell 15 causing said arbor to have a momentary rest at a predetermined point in its reciprocation, means for rotating said arbor corresponding to the reciprocation thereof to impart a rolling movement to said gear, 20 means for automatically stopping said arbor in said predetermined position, and means engageable with a tooth of said gear when the arbor is in said predetermined position for angularly locating the gear upon 25 said arbor.

8. In a gear grinding machine, the combination with a rotatable grinder wheel, of a work holding arbor, means for securing a gear upon said arbor, a cam for reciprocating said arbor having a dwell to provide 30

a momentary rest at a predetermined point in the reciprocation, means for rotating said arbor to impart a rolling movement to said gear, and a lever engageable with a tooth of said gear for angularly locating the gear 35 upon said arbor, said lever being normally held out of engagement with said gear.

9. In a gear grinding machine, the combination with a rotatable grinder wheel, of a relatively reciprocable carriage, an arbor 40 journaled on said carriage, and means for securing a gear upon said arbor, a cam for reciprocating said carriage, said cam having a dwell causing a momentary pause in the reciprocation of said carriage, means 45 for rotating said arbor to impart a rolling movement to said gear, and means for automatically stopping said arbor in said predetermined position, a lever pivotally secured to said carriage, a finger at one end 50 of said lever adapted to engage a tooth of said gear, for angularly locating the same upon said arbor, and a spring normally holding said finger out of engagement with said gear.

In testimony whereof we affix our signatures.

ALBERT J. OTT.
CONRAD L. OTT.
